UNITED STATES PATENT OFFICE.

JOSEPH E. JACKSON, OF GALESBURG, ILLINOIS.

CITY AND RURAL MAIL BOX.

Application filed October 1, 1923. Serial No. 665,927.

To all whom it may concern:

Be it known that I, JOSEPH E. JACKSON, a citizen of the United States, residing at Galesburg, in the county of Knox and State 5 of Illinois, have invented certain new and useful Improvements in City and Rural Mail Boxes, of which the following is a specification.

The present invention relates to city and 10 rural mail boxes, and has for its principal object to provide an indication for such structures which will be exposed upon operation of the receiving opening closure, and which is reset when the closure of the re- 15 movable opening is actuated.

Another object of the invention is to provide a novel device of this character which is simple in construction, efficient, advantageous in practice and comparatively inexpensive to manufacture.

A still further object of the invention is to provide the box with a receiving opening including means whereby mail may be inserted inwardly therethrough but may not 25 be extracted out of the opening, said opening also being constructed so that comparatively large mail may be inserted therethrough such as magazines and the like.

With the above and numerous other objects in view as will appear as the description progresses, the invention resides in certain novel features of construction, and the combination and arrangement of parts as will be hereinafter more fully described and 35 claimed.

In the drawing:

Figure 1 is a perspective view of the mail box embodying my invention;

Figure 2 is a fragmentary side elevation 40 thereof showing the signal in an operative position and the closure of the mail receiving opening in an open position;

Figure 3 is a similar view showing the signal in an operative position and the two 45 closures in an open position;

Figure 4 is a similar view showing the signal in an inoperative position and the closures in a closed position;

Figure 5 is a front elevation of the upper 50 portion of the box;

Figure 6 is a top plan view of the box

with the closure raised that is movable over the receiving opening;

Figure 7 is a section therethrough; and

Figure 8 is a similar section taken at a 55 different point.

Referring to the drawing in detail it will be seen that the mail box is indicated at 1 mounted on a suitable post 2 by means of plates 3 which are permanently fixed to the 60 sides of the box 1 and project rearwardly therefrom so as to be disposed along side of the post and held in engagement therewith by screws 4 or other fastening means. The upper end of this box 1 is open as is 65 disclosed to advantage in Figures 7 and 8 in fact there are two openings, one indicated at 5 which is the mail receiving opening and the other indicated at 6 which is the mail removal opening. A closure is provided for the mail-receiving opening in the form of a plate 7 having teeth 8 at its free edge. This plate 7 is normally held in a closed position by springs 9. A closure 10 70 is hinged at 11 intermediate the front and rear walls of the box over the mail removal opening 6 and its rear edge is disposed so as to overlie the free edge of the plate 7. Thus this plate 7 may only be pushed downwardly for insertion of mail and may not 75 be pulled upwardly for the removal of mail.

The rear edge of the closure 10 which overlies the free edge of the plate 7 is provided for a person to insert his hand into the mail 80 box through the mail receiving opening because upon the withdrawal of the hand the same will be caught by the teeth 8 and 13. This mail receiving opening and its closure plate 7 are constructed large enough so 85 that ordinary mail may be inserted in the box. The size of the ordinary mail box, however, would prevent the reception through this opening of large magazines. In order to allow for the insertion of such 90 magazines I provide the closure 10 with a semi-circular opening 14 and a plate 15 is hinged to the under side of the closure 10 for closing this opening 14. The closure plate 15 is normally held in the closed position by 95 spring 16. The free edge of this closure is provided with teeth 17 which will normally

overlie the adjacent teeth 8 of the closure plate 7. With the aid of this additional opening 14 it is evident that larger magazines may be rolled up and inserted into the mail box through the opening 14 and a portion of the opening 5.

5 A storm closure 18 is hinged to the upper rear wall of the box 1 and when closed will overlie the openings 5 and 14 so that in order 10 to put mail into the box it is necessary to lift this closure 18.

An indicating device or target 20 is hinged to the rear wall of the box 1 and in its non-indicating position will be disposed as shown 15 in Figure 4 that is so as to overlie the storm closure 18. A stop bar 21 is fixed to the rear wall of the box 1 and is slanted rearwardly therefrom and extends above the box so that when the target 20 is swung to a raised or 20 indicating position it will rest against this stop as is clearly shown in Figure 2. Under normal conditions the box is in the position shown in Figure 4 that is when the box is empty. When the mail man delivers the 25 mail it is necessary to raise the closure 18 thus placing the target in an indicating position so that it may be seen from a distance and the occupant of the house or residence will know that mail has been delivered. 30 When the target is in its indicated position the spring lip 21' frictionally engages the stop bar 21 thus preventing the same from being blown or easily moved to its non-indicating position.

35 In order to remove the mail from the box 1 it is necessary to raise the closure 10 by removal of a pad lock 24 or other suitable locking means. I, therefore, provide this closure 10 with engaging means for association with the target so that when said closure 10 is replaced in its closed position it will bring the target to a downward or non-indicating position. This engaging means consists of a dog 25 pivoted in brackets 26 40 and retained in an active position by a spring 27. The target 20 is provided with a slot 28 through which the dog will go when the closure 10 is raised and a latch 29 of the dog 25 will engage the bottom edge of 45 this slot as shown to advantage in Figure 3. As the closure 10 is moved to a closed position from that position shown in Figure 3 it will be seen that the dog 25 will disengage from the bottom edge of the slot 28 of the 50 target when the target has been moved sufficiently so that it will swing to a closed position of its own accord. It is also to be noted that the target will move the storm closure 18 to a closed position when actuated to a 55 non-indicating position as just described.

While the preferred embodiment of my invention has been described in detail, it will be understood that I do not wish to be limited to the particular construction set forth, 60 since various changes in the form, material,

proportion and arrangement of parts and in the details of construction may be resorted to without departing from the spirit or scope of the invention or destroying any of the advantages contained in the same, heretofore 70 described and defined in the said drawing and claims.

What is claimed is:

1. A city and rural mail box having receiving and removal openings, closures for 75 said openings, an indicator actuated to an indicating position by one of said closures, and means associated with the other closure for engaging the indicator and returning it to a non-indicating position when said closure just mentioned is moved to an open and closed position.

2. A city and rural mail box having receiving and removal openings, closures for 80 said openings, an indicator actuated to an indicating position by one of said closures, means associated with the other closure for engaging the indicator and returning it to a non-indicating position when said closure just mentioned is moved to an open and 85 closed position and also returning the first closure, that is, the one that actuates the indicator to an indicating position to a closed position simultaneously with the indicator being moved to a non-indicating position. 90

3. A city and rural mail box having receiving and removal openings, an indicator hinged to the box, a closure for the removal opening of the box, a second closure for the receiving opening of the box disposed between the first closure and the indicator, so that when the second closure is raised it will move the indicator to an indicating position and means on the first closure for engaging the indicator when said first closure is raised to an open position whereby said indicator will be returned to a non-indicating position and said second closure moved to a closed position when the first closure is returned to a closed position. 100

4. A city and rural mail box having receiving and removal openings a closure for the removal opening, an indicator hinged to the box, a spring pressed dog on the closure adapted to engage the indicator when in an indicating position when the closure is open so that upon closure of the closure the indicator will be returned to a non-indicating position all in the manner and for the purpose specified. 110

5. A city and rural mail box having receiving and removal openings, a closure for said removal opening, a spring-pressed closure plate for said receiving opening, said closure provided with an opening communicating with the receiving opening in the box and a spring pressed closure associated therewith all in the manner and for the purpose specified. 115

6. A city and rural mail box having re- 120

ceiving and removal openings, a closure for the removal opening, an indicator hinged to the box, a stop bar fixed to the box so that when said indicator is raised to an indicating position it will rest against said stop bar, and means on the closure for engaging the indicator when it is disposed in an indicating position and said closure is raised to an open position whereby when said closure is returned to a closed position it will actuate the indicator to return to a non-indicating position all in the manner and for the purpose specified.

7. A city and rural mail box having receiving and removal openings, a closure for the removal opening, an indicator hinged to the box, a stop bar fixed to the box so that when said indicator is raised to an indicating position it will rest against said stop bar, means on the closure for engaging the indicator when it is disposed in an indicating position and said closure is raised to an open position whereby when said closure is returned to a closed position it will actuate

the indicator to return to a non-indicating 25 position said means including a spring-pressed latch.

8. A city and rural mail box having receiving and removal openings, closures for said openings, an indicator hinged to the 30 box, said indicator provided with a slot, a spring-pressed dog mounted on the closure over the removal opening, said indicator adapted to be moved to an indicating position by the closure over the receiving opening, said spring-pressed dog adapted to be inserted through the slot of the indicator when the closure over the removal opening is raised so as to engage the indicator and return the same to a non-indicating position 40 when the closure over the removal opening is returned to a closed position.

In testimony whereof I affix my signature in presence of two witnesses.

JOSEPH E. JACKSON.
